UNITED STATES PATENT OFFICE

ROBERT HUNTER CAMPBELL, OF UPPER EDMONTON, LONDON, ENGLAND

FIRE EXTINGUISHER

Application filed August 29, 1932, Serial No. 630,929, and in Great Britain October 12, 1931.

This invention relates to fire-extinguishers of the kind comprising a vessel containing a fire-extinguishing medium, and means for sealing the outlet of the said vessel; and this invention has for its object to provide an improved fire-extinguisher of the aforesaid kind which is ready for immediate use and wherein the fire-extinguishing medium can be more easily and quickly liberated.

According to this invention the fire-extinguishing medium in the vessel is subjected to pressure before the said vessel is sealed and is maintained under pressure until liberated, and the outlet of the said vessel is provided with a closure of soft, or plastic, metal of relatively low tensile strength having a hollow part at its inner end open to the interior of the vessel which closure can be broken, when desired at its hollow part to liberate the said fire-extinguishing medium.

I will particularly describe this invention with reference to the accompanying drawings in which Figure 1 shews in elevation a preferred construction of sealed fire-extinguisher in accordance with this invention and Figure 2 is a similar elevation shewing the closure thereof fractured thereby liberating the fire-extinguishing medium. Figure 3 is a section, drawn to a larger scale than the said Figures 1 and 2, of the lower end of the said fire-extinguisher and its closure. Figures 4 and 6 are elevations shewing alternative means for fracturing the closure of the fire-extinguisher, and Figures 5 and 7 are respectively sections on the line A, B, Figure 4, and C, D; Figure 6.

The fire-extinguisher consists of a solid drawn, pressed or soldered vessel 1 of any suitable metal having secured in its outlet a tubular metal connection 2 in communication with the interior of the said vessel and having an outlet orifice 2a adapted to receive and to have secured therein a closure 3 of soft, or plastic metal of relatively low tensile strength, such for example as the closure for capsules described and illustrated in the specification of British Letters Patent No. 253,744, granted to me June 24, 1926 (acceptance date), wherein the said closure is

provided with an outwardly projecting stem-like portion 3a and is longitudinally hollow from its inner end to within a suitable distance from its outer end, so that the latter can be easily broken at the said hollow part. The outlet orifice 2a is internally screw-threaded to receive the soft, or plastic, metal closure 3 and has a shoulder 2b therein which constitutes a seating for the said closure. The vessel 1 is charged to about two-thirds of its capacity with fire-extinguishing medium (which may for example be carbon tetrachloride) after which the soft metal, or plastic, closure 3 is inserted in the orifice 2a. Gas under pressure (such for example as carbonic acid gas) is then conveyed to the orifice 2a and passes, between the internal screw-threads therein and the soft metal, or plastic, closure 3 and the rear end thereof and its seating 2b into the vessel 1. When sufficient gas has been admitted into the vessel 1 to obtain the desired pressure it is sealed by compressing the soft, or plastic, metal closure 3 in the orifice 2a. This may be effected by a press, the plunger of which presses upon the said closure 3 and causes it to expand laterally and flow into the internal screw threads in the orifice 2a thereby hermetically closing the said vessel.

The outwardly projecting stem-like portion 3a of the closure 3 may be fractured, when desired, by snapping it transversely and this may be facilitated by angular movement of a lever 4 screwed, or otherwise secured, thereto. Fracture of the said stem-like portion 3a immediately liberates the fire-extinguishing medium which passes from the vessel through the now open ended hollow portion of the said closure remaining in the orifice 2a of the tubular connection 2 as shewn in Figure 2.

If desired a relatively thin tube 5 of harder metal than that of the closure 3 may be inserted in the hollow length thereof as shewn in Figure 3, so that, upon fracturing the portion 3a thereof, the said tube will prevent any distortion of the orifice and ensures an unobstructed outlet for the fire-extinguishing medium.

Instead of fracturing the projecting por-

tion 3a of the closure 3 by means of the lever 4 screwed thereon as aforesaid, a lever 5 may be provided for this purpose pivoted to the tubular connection 2 and connected to the 5 said projecting portion of the closure by a flanged socket 6 screwed onto the outer end of the said projecting portion as shewn in Figures 4 and 5. The lever 5 may be mainly of U-shape in cross-section the parallel side 10 members thereof being pivoted at their lower ends to the tubular connection and the socket 6 being passed through a hole in the central member of the said lever and screwed up so that its flange 6a engages with the outer side 15 of the said member. Fracture of the projecting portion 3a to liberate the fire-extinguishing medium is effected by turning the lever 5 on its pivot in the direction of the arrow E.

If desired the fire-extinguisher may be re- 20 movably held by spring clips 7 secured to a bracket 8 which in turn is secured to a wall, or its equivalent, as shewn in Figures 6 and 7. In this example the projecting portion 3a of the closure has a flanged socket 6 screwed 25 onto its outer end as in the construction shewn in Figures 4 and 5. The bracket 8 has a slot 8a formed therein having an enlarged upper portion to permit the flange 6a to pass therethrough and a reduced lower portion to 30 permit only the socket to pass therethrough. The fire-extinguisher is placed in position on the bracket 8 by tilting it, inserting the flange 6a of the socket 6 into the enlarged portion of the slot 8a, lowering the said ex- 35 tinguisher until the said socket engages the reduced portion of the said slot and then pushing it into its vertical position between the spring clips 7. When the fire-extin- 40 guisher is required for use, it is pulled, by an angular movement, from the spring clips 7, thereby causing the projecting portion 3a of the closure to be fractured by the socket 6 which is held against angular movement by the engagement of its flange 6a with the 45 bracket 8.

The aforesaid fire-extinguishers may, after use, be again recharged for future use. This can be easily effected by un-screwing the portion of the closure 3 remaining in the tubu- 50 lar connection 2, re-charging the vessel 1 as before and then again sealing the outlet of the said connection by another soft, or plastic metal closure 3 as before.

It will thus be seen that in fire-extin- 55 guishers constructed in accordance with this invention the fire-extinguishing medium is contained under pressure in a sealed vessel and is ready for immediate use.

What I claim is:

60 1. In a fire extinguisher including a vessel having a suitable quantity of fire extinguishing fluid stored therein under pressure, and a hollow frangible discharge outlet mem- 65 ber having a closed outer end in communica- 123 tion with the interior of the vessel to dis-

charge the contents thereof when said member is broken, the combination with the vessel and outlet member of a screw-threaded connection carried by the vessel, a cooperat- 70 ing screw-threaded portion carried by the outlet member, the outlet member including the screw-threaded portion thereof being composed of a relatively soft, plastic metal of relatively low tensile strength which may be flowed under pressure to form a fluid-tight 75 seal between the cooperating screw-threaded portions of the connection and outlet member, and a relatively hard metal hollow core member within the soft metal discharge member whereby to sustain the walls thereof 80 against collapse and distortion when said outlet member is fractured to release the contents of the vessel.

2. In a fire extinguisher including a vessel having a suitable quantity of fire extinguishing fluid stored therein under pressure and a hollow frangible discharge outlet member having a closed outer end in communication with the interior of the vessel to discharge the contents thereof when said member is broken, the combination with the vessel and outlet member of a screw-threaded connection carried by the vessel, a cooperating screw-threaded portion carried by the outlet member, the outlet member being composed of a 90 relatively soft, plastic metal of relatively low tensile strength, and a relatively hard metal hollow core member within the soft metal discharge member whereby to sustain the walls thereof against collapse and distortion 100 when said outlet member is fractured to release the contents of the vessel.

In testimony whereof, I have signed my name to this specification at London, Eng- 105 land, this 16th day of August, 1932.

ROBERT HUNTER CAMPBELL.
